REFRIGERATOR LATCH

Filed Sept. 28, 1929

Inventor.
ADOLPH RUBIN,
By John H. Kennedy,
His Attorney

UNITED STATES PATENT OFFICE

ADOLPH RUBIN, OF ST. LOUIS, MISSOURI

REFRIGERATOR LATCH

Application filed September 28, 1929. Serial No. 395,892.

This invention relates to latches for refrigerator doors.

In the ordinary latch for refrigerator doors, the bolt must strike the bevel portion 5 of the keeper in order to place it in position to snap behind the catch and keep the door in position. This causes a strain on the latch, its parts and fastenings.

An object, therefore, of this invention is 10 to provide a latch with a trigger of simple and durable construction which will hold the bolt in withdrawn position while the door is open and release the bolt when the door is closed.

15 Another object is to provide a latch which is simple of construction, economical to manufacture, positive in operation, durable in use, and easy of repair.

Other objects will appear from the following description taken in connection with the accompanying drawings, in which:

Fig. 1 is a rear elevation;

Fig. 2 is a sectional view taken on line 2—2,

Fig. 1;

25 Fig. 3 is a sectional view taken on line 3—3,

Fig. 2.

As illustrated, the latch apart from the trigger element and the keeper, is identical with the latch described in application of this 30 applicant Serial No. 333,765, filed January 21, 1929. It comprises a base or casing having attaching flanges with a latching element pivotally mounted thereon, the latching element comprising integrally a handle, a sleeve, a lever and the bolt attached to the 35 lever.

The base, or casing, of the latch may be of any preferred form. As shown in the drawings, the casing 1 has the attaching flanges 2. 40 Supported on the casing are two ears 3. Pivotally mounted on the ears 3, by means of the pin 4 is the latching element. The pin 4 may be secured in place by a screw or a key inserted at 5.

45 The latching element comprises the sleeve 6 to which is attached the handle 7, and a lever or arm 8 supporting the bolt 9. This element is preferably formed integrally and may be cast in one piece.

50 A torsion spring 10 is placed within the

sleeve 6 about the pin 4, with one end in engagement with the sleeve at 11 and the other end in engagement with a bushing 12. The tension of the spring may be secured or adjusted by means of a stud 13 passing through an ear 3 into one of the several holes 14 in the bushing. A hole 15 is provided in the periphery of the bushing to accommodate a pin so that the tension may be held while adjustment of the stud 13 is being made.

The latch may have mechanism to permit its being opened from the inside of the door. A rocker shaft 16 is journaled in the casing and has attached to it the lever 17 which engages the forked lever 18 integral with the sleeve 6 and, therefore, integral with the bolt. On the inside of the rocker shaft is keyed the hand lever 19. Means may be provided to open the door by the foot, as by the pivoted foot pedal 20 connected by the link 21 70 to the hand lever 19.

A trigger 22 in the form of a lever of the first class, is pivotally mounted on a pin 23 projecting laterally from the bolt 9. One end of the trigger has a right angle arm 24 extending outside the casing, adapted to strike an abutment on the keeper. The other end of the trigger is provided with a surface 25 adapted to engage a shoulder 26 formed in the top of the casing. Tension is secured by the 80 spring 27 fastened at one end through a hole in the pin 23 and the other end secured against the trigger.

It will thus be seen, when the door is open, the surface 25 of the trigger moves into engagement with the shoulder 26 in the casing and holds the bolt in withdrawn position. When the door is closed the arm 24 strikes the abutment on the keeper, releasing the trigger and the bolt, permitting the bolt to move 90 into its keeper.

It will thus be seen that the invention accomplishes its purpose. A latch is provided in which the bolt is held in withdrawn position until the door is closed, by means of a simple and efficient trigger. A latch is provided which is simple of construction, economical to manufacture, positive in operation, durable in use, and easy of repair.

With reference to the latch, apart from the 100

trigger, while a particular construction of the latch, is shown and described, it is obvious that this invention may as well be used in constructions materially different from that shown.

5 The invention claimed in this application is related to invention in application Serial No. 395,891, filed September 28, 1929, in which application is claimed subject matter common to the two applications.

10 It is also to be understood that the invention is not limited to the means specifically illustrated and described in connection with the trigger but that changes may be made, within the scope of the claims, without departing from the spirit of this invention.

15 Having thus described the invention, what is claimed is:

20 1. A refrigerator door latch including a casing having attaching flanges, a bolt adapted to cooperate with a keeper and a trigger pivotally mounted on said bolt, said trigger comprising a lever of the first class, a projection from one end of said lever adapted to strike the keeper to release the trigger, the other end of said lever having a surface adapted to engage a shoulder on the casing to retain the bolt in withdrawn position when the door is open.

25 2. A refrigerator door latch including a casing having attaching flanges, a bolt adapted to cooperate with a keeper, a trigger pivotally mounted on said bolt, said trigger comprising a lever of the first class, a projection from one end of said lever adapted to strike the keeper to release the trigger, the other end of said lever having a surface adapted to engage a shoulder on the casing to retain the bolt in withdrawn position when 30 the door is open, and a spring to secure tension between the trigger and the bolt.

35 3. A refrigerator door latch comprising, a casing, a latching element pivotally mounted on the casing, said latching element comprising integrally a handle, a sleeve, a lever and a bolt projecting laterally from said lever, and a trigger pivotally mounted on said bolt adapted to engage a shoulder on the casing above the trigger and hold the bolt in withdrawn 40 position when the door is open.

45 In testimony whereof I affix my signature this 12th day of Sept., 1929.

ADOLPH RUBIN.
